UNITED STATES PATENT OFFICE.

CHARLES W. PINKNEY, OF SMETHWICK, ASSIGNOR TO THE TANGYES,
LIMITED, OF SOHO, ENGLAND.

GAS-ENGINE.

SPECIFICATION forming part of Letters Patent No. 499,935, dated June 20, 1893.

Application filed October 27, 1891. Serial No. 409,999. (No model.) Patented in England January 2, 1891, No. 103.

To all whom it may concern:

Be it known that I, CHARLES WILLIAM PINKNEY, engineer, a subject of the Queen of Great Britain and Ireland, residing at 5 Raglan Road, Smethwick, in the county of Stafford, England, have invented certain improvements in and connected with engines in which gas generated from petroleum or other liquid hydrocarbon is employed, of which the following is a specification, and for which Letters Patent have been obtained in Great Britain, No. 103, dated January 2, 1891.

My improvements relate to engines to be worked by the combustion of gasified petroleum or other liquid hydrocarbon and air, the object of my invention being to provide a simple and efficient engine whereby the utilization of the petroleum or other liquid hydrocarbon employed is efficiently effected and 20 is under control. The point or time of ignition of the explosive charge may moreover be regulated so that it is caused to take place when any desired degree of compression of the charge has taken place, the ignition being 25 effected without the employment of an igniting tube being necessary.

I will describe my invention with reference to the accompanying drawings premising however that I do not limit myself to the precise details shown therein.

I will refer to the liquid hydrocarbon for brevity as "petroleum."

Figure 1 shows in longitudinal section and Fig. 2 in transverse section so much of an engine as is necessary to illustrate my invention. Fig. 3, is a section of the valve drawn to a larger scale. Fig. 4, is a sectional view of an arrangement for pumping air into the combustion chamber, and Fig. 5, is a sectional view of a detail hereinafter referred to.

A is the cylinder in which the piston works and C is the combustion chamber.

D is the air and petroleum inlet valve in the valve box d.

45 e is the oil inlet passage.

d² is the spring which closes the valve D by bearing on the nut d³.

The air and petroleum inlet is situated as shown near to the cylinder end of the combustion chamber. The casing C' of the com-

bustion chamber is for the purpose of retaining the heat thereof.

C⁴ is the combustion chamber cover and C³ is a water circulating passage around the cylinder end of the combustion chamber. 55

C⁵ is the inlet water circulating pipe for supplying water to the passage C³ from the pipe A⁴ by which water is passed into the jacket A² of the cylinder A.

C⁶ is the outlet water circulating pipe from the passage C³ and A³ is the outlet water circulating pipe from the jacket A².

C² are water passages which may be used to give communication from the jacket A² to the passage C³. If desired the pipe C⁵ may be dispensed with and water be supplied to the space C³ from the jacket A² entirely by a passage or passages such as C² in which case the said passage, or each such passage, may be provided with a regulating screw as shown at 7c to regulate the admission of the water.

I is the lamp which may be used in starting the engine it being supplied with petroleum by the pipe j to be vaporized and burned.

P is the exhaust passage.

H (Fig. 2) is the petroleum inlet pipe provided with the cock h'.

m is the air inlet passage.

My invention being most suited to work on what is known as the two to one cycle I will 80 describe it in connection with such working.

To start the engine I burn the lamp I underneath the combustion chamber C and when the said chamber C becomes sufficiently heated (usually in a few minutes) I open the petroleum cock h' and cause the engine piston to make its charging stroke. The air will then pass through the passage m into the valve box d. The petroleum will pass or be forced from any suitable tank or holder 90 through the passage e into the said valve box d where it will mix with the air and they will pass into the combustion chamber C and cylinder A in the form of well mixed air and petroleum which is not however yet vaporized. 95 During the return, or compression, stroke of the piston the mixture of air and petroleum is forced by the piston into the now hot combustion chamber C the temperature of which is very much higher at the outer or smaller 100

- end than it is at the inner or larger end owing to the water circulation at C^3 and contact with the cylinder A being cooled by the water jacket A^2 . While the mixture is being forced into the combustion chamber C the heat of the said chamber converts the mixture into an explosive vapor or gas and, when this mixture is at or about the highest point of compression, this compression, assisted by the heat thereof, causes it to ignite and drive the piston outward and so gives motion to the crank shaft. On the reverse stroke of the piston the exhaust valve (not shown in the drawings but situated in the passage P) is opened (which may be done by a cam on a second motion shaft in the usual way) and the exhaust gases are driven out of the cylinder by the piston and so one complete cycle of operations is performed. The water passage C^3 round the combustion chamber C prevents ignition taking place too soon, the said jacket extending toward the small end of the said chamber to a greater or lesser distance according to the period of ignition required.
- 25 I may fix a chamber T containing a valve t (see Fig. 3 showing this chamber and valve drawn to a larger scale) on the small end of the combustion chamber C in place of the cover C^4 or in any other suitable position so as to be in communication with the chamber C.
- t^2 is a collar (fixed by a set pin t^3) on the valve spindle for adjusting the amount of lift of the valve t .
- 30 t^4 is a screw for adjusting the degree of closing of the valve t by its spindle bearing on the said screw and t^5 is a lock nut therefor.
- t^6 is a cover for giving access to the adjusting collar t^2 and screw t^3 .
- 40 During compression the screw t^4 keeps the valve t more or less from its seat so that the gases can either be let freely into the chamber T or be impeded to any desired extent in their passage thereinto, for the purpose of regulating ignition as hereinafter explained.
- 45 The inlet valve D being situated, as shown, near to the large end of the combustion chamber C next the cylinder when the piston makes its charging stroke the petroleum and air will pass into the cylinder A through the valve D, and the exhaust gases (due to a previous ignition) in the chamber C will be very little disturbed. During compression the exhaust gases in the chamber C will be forced back by the new charge of petroleum and air, for a considerable distance toward the small end before the part in the said combustion chamber C which is hot enough to cause ignition is reached by the said charge. This will take
- 50 some little time, it being sufficient to allow the crank pin to arrive at the most favorable position for the explosion. If the ignition should be too late and the valve t and chamber T be used I then raise the said valve t from its seat by the adjusting screw t^4 so that during compression the exhaust gases will

more freely pass the valve t and enter the chamber T and allow the charge of petroleum and air the sooner to reach the part of the chamber C which is hot enough to cause an earlier ignition. The water in the passage C^3 and the extension of it back to the required extent from the cylinder end of the combustion chamber will prevent too early ignition. I may use the branch supply pipe C^5 and the outlet pipe C^6 or the passages C^2 (as aforesaid) or both to supply the passage C^3 with cooling medium or in large engines a pump may be used to force the cooling medium through the passage C^3 .

80 To govern this engine I may use any suitable arrangement such for instance as the well known method of "spragging" the exhaust valve open as in the "Otto" gas engine for instance thus preventing (except when the said valve is not spragged open) the inlet valve D, with the aid of the light spring d^2 , leaving its seat during the charging stroke of the piston and so then neither air nor petroleum is allowed to enter the cylinder during 85 the time the engine is running beyond its proper speed.

Fig. 4 represents an arrangement which may be used in an engine constructed according to my invention for pumping air into 90 the combustion chamber C to time or assist in timing the period of ignition of the charge. The air thus forced into the combustion chamber dilutes the vapor already formed by the mixture of the air and liquid hydrocarbon to 95 such an extent as to render the vaporized mixture explosive.

8 is the pump barrel and 9 the plunger.

10 is the inlet valve and 11 the outlet valve kept to their seats by springs as shown when 105 not opened by the action of the pump.

12 is the passage by which air is delivered into the combustion chamber by the pump which is worked by an eccentric q^8 and rod operated by the second motion shaft Q^2 .

13 is a relief cock which is opened to allow the air to flow into the atmosphere when it is not required to be passed into the combustion chamber or which cock is partly opened to regulate the amount of air to be delivered 115 into the main cylinder. C^3 are water circulating spaces which serve to keep the parts adjacent to them cool.

When very steady running is required and the petroleum is drawn into the combustion chamber by the vacuum caused by the charging stroke of the piston instead of being forced thereinto by a pump or the like I prefer to regulate the quantity of petroleum to be vaporized according to the speed of the engine. 120 For this purpose I may use an ordinary center spindle high speed governor U to the spindle of which is directly connected a conical valve u with its stem u^2 guided in the casing u^3 of the valve (as shown in Fig. 5) and made 125 to cover the petroleum inlet passage H so that when the speed of the engine is excessive the

governor U will operate the conical valve u so that less petroleum will pass therethrough, but when the speed of the engine is reduced to about normal speed the governor U will 5 raise the conical valve u and so give more petroleum to the engine.

k is a cup to receive the petroleum from the pipe K before it passes through the valve and *k*² is an overflow to a petroleum receiver.

10 Having now particularly described and ascertained the nature of my said invention and in what manner the same is to be performed, I declare that what I claim is—

15 1. In an engine of the character herein set forth, the combination with the cylinder, of a combustion chamber at one end thereof, said chamber being provided with inlets for the explosive mixture near the cylinder end thereof and with means such as a water jacket 20 for keeping that end only relatively cool, whereby the explosion of the mixture is regulated substantially as described.

25 2. In a petroleum or other liquid hydrocarbon engine the combination with the cylinder, the combustion chamber joined to one end thereof and forming a continuation of the same, and the inlet valve in the combustion chamber, of an expansion chamber communicating with the outer end of the combustion 30 chamber, and an adjustable regulating valve in the communicating passage between the

said combustion and expansion chambers, substantially as described.

3. In a petroleum or other liquid hydrocarbon engine the combination with the cylinder, 35 the combustion chamber at one end thereof and the inlet valve in the combustion chamber, of a passage around the combustion chamber at the cylinder end thereof only, and means for supplying said passage with a cooling medium, substantially as described. 40

4. In a petroleum or other liquid hydrocarbon engine the combination with the cylinder, the combustion chamber at one end thereof and the inlet valve in the combustion chamber, of a jacket around the cylinder adapted 45 to contain a cooling medium, a passage around the combustion chamber at the cylinder end thereof only, and means for connecting the said passage with the interior of the jacket 50 around the cylinder, substantially as described.

In testimony whereof I have signed my name to this specification in the presence of two subscribing witnesses.

C. W. PINKNEY.
